SAFETY RAZOR

Joseph E. McWilliams, New York, N. Y., assignor
to American Safety Razor Corporation, Brook-
lyn, N. Y., a corporation of Virginia

Application June 2, 1933, Serial No. 674,089

9 Claims. (Cl. 30—59)

This invention relates to safety razors and more particularly razors of the type in which a single edge blade is held in position on the blade seat by a pivoted cover and it is an object of this 5 invention to provide a razor of the type described of improved construction and having a cover provided with means which engage with the blade to positively position the blade in the proper shaving position. It is also an object of this 10 invention to provide a blade of such construction that it will cooperate with the cover during the closing movement of the cover so as to be positively positioned thereby.

This invention is an improvement of the construction disclosed in the United States Patent to Dalkowitz No. 1,773,614.

In the drawing:—

Figs. 1, 2, 3, and 4 are partial vertical sections of a razor constructed in accordance with 20 this invention and showing different positions of the cover in its movement towards closed position when a blade is in position in the razor;

Fig. 5 is a view similar to Figs. 1 to 4 but showing the limit of movement of the cover towards closed position when no blade or a blade of improper construction is in the razor;

Fig. 6 is a horizontal section taken through the cover above the blade seat as on the line 6—6 of Fig. 1 and showing the seat in plan view;

Fig. 7 is a horizontal section taken on line 7—7 of Fig. 4 and showing a blade in position on the blade seat; and

Figs. 8 and 9 are plan views of blades designed to cooperate with the holder of Figs. 1 to 5.

In the drawing the invention is shown applied to a safety razor of the type shown in the patent to Dalkowitz, No. 1,773,614, issued August 19, 1930, comprising a blade seat 1 having a hollow stem portion 2 which is secured to the tubular handle 3. Along one edge of the seat extends a guard portion 5 at the ends of which are the stops 4 which position the blade 6 for shaving. Rotatably mounted in the seat 1 is a shaft 8 having a pinion 10 thereon which meshes with the rack portion 12 of a wedge 14. At the ends of the shaft 8 are the fixed arms 16 to which, at their outer ends, is pivotally connected a cover 18. The wedge 14 has a projection 20 provided with a cam face 22 which is engaged by the conical cam face 24 of the pin 26 mounted in the handle 3 and projecting from the free end thereof. The pin 26 has a screw-thread engagement with the handle 3 and is moved longitudinally of the handle by rotation therein. A spring 28, confined 50 between the wall of the hollow stem portion 2

and a face of the projection or abutment 20 tends to force the wedge 14 to the left as shown in Figures 1 to 5. The blade 6, as shown in Figs. 1—8 inclusive is of the single edge type having a cutting edge 29 and a reinforcement 30 which embraces the opposite edge of the blade and extends from end to end of the blade. At its center the reinforcement 30 is partly cut away exposing the blade at this point and leaving a narrow connecting portion 32 which forms an abutment above the exposed portion of the blade. The seat 1 is cut away to form a recess to receive the reinforcement and permit the blade to lie flat on the blade seat. The recess is of slightly greater width than the reinforcement 30 and the shoulder 15 5 formed thereby is slightly in advance of the extreme position of the reinforcement when the blade is in proper shaving position. The seat 1 is also recessed at its center to form a shoulder 36 in back of the shoulder 34. To ensure the blade 20 being held in the proper shaving position when the cover 18 is in closed position there is provided a pawl 38 pivotally mounted, as at 39, on the cover 18 and positioned in line with the abutment 32 of a blade properly positioned on the blade 25 seat. In the open position of the cover 18 the pawl 38 does not extend over the blade seat sufficiently to interfere with the insertion or removal of a blade.

In the modified form of blade shown in Fig. 9 30 an abutment 42 is secured to the blade in position to be engaged by the pawl. The abutment 42 may be secured to the blade in any suitable manner or be in the form of a rivet.

In the operation of the razor, with the razor 35 in the open position and a blade on the blade seat, as shown in Fig. 1, rotating the stem 26 to move the stem towards the wedge 14 causes the cam surface 24 of the stem to force the wedge 14 to the right by its engagement with the cam face 40 22, the abutment 20 compressing the spring 28. Movement of the wedge 14 to the right causes the rack portion 12 thereof to rotate the shaft 8 and the crank arms 16, and by reason of the pivotal engagement thereof with the cover and 45 the contact of abutments 40 therewith causes the crank arms 16 to shift the cover 18 toward the blade seat 1, eventually bringing the cover to the position shown in Fig. 3, in which the cover 18 bears against the blade 6 and the wedge 14 is 50 about to pass beneath the rear edge 18a of the cover. As the cover 18 is brought to this position the pawl 38 drops and rests upon the blade 6 in back of the abutment 32. As the wedge 14 is operated to pass beneath the rear edge of the 55

cover 18, the crank arms 16 shift the cover 18 along the blade 6 and the pawl 38 engaging with the abutment 32 forces the blade 6 into engagement with the stops 4, thus positioning the blade 5 for shaving and securing the blade firmly in position, the pawl being held by the cover 18 which is secured in position by the wedge 14 engaging the rear edge 18a of the cover.

Reversing the rotation of the stem 26 permits 10 the spring 28 to force the wedge 14 to the left, withdrawing the wedge from beneath the rear edge of the cover 18 and operating the crank arms 16 to at first slide the cover on the blade 6 until the abutments 40 in the sides of the cover 15 engage with the crank arms 16 whereupon, the wedge having been withdrawn from beneath the rear edge of the cover, the cover is rotated about the shaft 8. This movement of the cover 18 withdraws the pawl 38 from engagement with the 20 abutment 32 and leaves the blade 6 free to be removed from the razor. Where blades which lack the abutment 32 are used, the pawl 38 will be ineffective to position the blade against the stops 4, and where the rear edge of the blade is cut so 25 as to provide an abutment the pawl 38 will drop below the edge of the blade and engage with the shoulder 36 unless supported by the blade and stop the movement of the cover 18 towards the blade in a position such as shown in Figure 5, in 30 which the blade is not held either by the cover 18 or the pawl 38, thus giving a clear indication to the user that the razor is not properly adjusted for shaving.

What is claimed is:—

35 1. In a safety razor, a blade seat, a cover, means pivotally supporting said cover from said seat, means operating said cover towards said seat, a blade on said seat having an abutment thereon and a gravity operated pawl on said cover engaging said abutment to operate said blade to a predetermined position on said seat as said cover is moved toward said seat.

40 2. In a safety razor, a blade seat, a cover, means pivotally supporting said cover from said seat, means operating said cover towards said seat and a pawl on said cover for securing a blade in a predetermined position on said seat when said cover is in closed position and a shoulder on said seat engageable by said pawl to limit closing of 45 said cover.

45 3. In a safety razor, a blade seat, a cover, means pivotally supporting said cover from said seat, means operating said cover towards said seat, a pawl pivotally mounted on said cover, a shoulder 50 on said seat engageable by said pawl to prevent movement of said cover to seat engaging position and a blade on said seat having an abutment engageable by said pawl to position said blade as said cover is moved into engagement with said seat, said blade preventing engagement of said shoulder by said pawl.

60 4. In a safety razor, a blade seat, a cover, means pivotally supporting said cover from said seat,

means operating said cover to engage said seat, a pawl pivotally mounted on said cover, a blade on said seat having an abutment located inwardly of the rear edge of said blade and engageable by said pawl to position said blade as said cover is moved toward said seat, said blade supporting said pawl while said pawl engages said abutment. 5

5. In a safety razor, a blade seat, a cover, means pivotally supporting said cover from said seat, means operating said cover to and from said seat, 10 a pawl pivotally mounted on said cover, means on said seat engageable by said pawl to limit movement of said cover toward said seat and a blade on said seat having an abutment engageable by said pawl to position said blade on said seat as said cover is moved towards said seat, said blade preventing engagement of said pawl with said seat and the limiting of the movement of said cover towards said seat. 15

6. In a safety razor, a blade seat, a cover, means pivotally supporting said cover from said seat, means operating said cover to and from closed position on said seat, a blade on said seat, a reinforcement along the rear edge of said blade having a recess therein forming an abutment and a pawl pivotally mounted on said cover and movable to rest on said blade in engagement with said abutment to position said blade as said cover is moved to closed position. 20

7. In a safety razor, a blade seat, a cover, means pivotally supporting said cover from said seat, means operating said cover to and from said seat, a blade on said seat having an abutment thereon and a pawl pivotally mounted on said cover and movable to rest on said blade in engagement with 25 said abutment to position said blade as said cover is moved to closed position. 30

8. A blade comprising a blade body having a shaving edge along one end and a reinforcing member along the other end, said member being 40 raised above the blade body and having a portion thereof extending inwardly from said end cut away so as to present an abutment shoulder spaced inwardly along the unbroken surface of the blade from said other end for a substantial distance, whereby an advancing element brought into and held in engagement with said blade surface within said cut-away portion and moved forwardly, will slide along said surface and will then engage said abutment and advance the blade and 45 will be supported above the blade body by the adjacent blade surface during said motion. 50

9. In a safety razor, a blade seat, a cover, means pivotally supporting said cover from said seat, means operating said cover to and from said seat, 55 a shoulder on said seat, a pawl pivotally mounted on said cover and engageable with said shoulder to limit closing of said cover and a blade on said seat having an abutment thereon engageable by said pawl to position said blade upon movement 60 of said cover to closed position, said blade preventing engagement of said pawl and shoulder.
